J. E. BURNS.
WINDOW SEAT.
APPLICATION FILED DEC. 10, 1917.

1,274,000.

Patented July 30, 1918.

UNITED STATES PATENT OFFICE.

JOHN E. BURNS, OF NORTHPORt, NEW YORK.

WINDOW-SEAT.

1,274,000.

Specification of Letters Patent. Patented July 30, 1918.

Application filed December 10, 1917. Serial No. 206,510.

To all whom it may concern:

Be it known that I, JOHN E. BURNS, a citizen of the United States, residing at Northport, Long Island, in the county of Suffolk and State of New York, have invented certain new and useful Improvements in Window-Seats, of which the following is a specification.

This invention relates to window shelves, and more particularly to a device which is adapted to be secured to a window casing so as to project outwardly from the same and form a support for a person washing or repairing the window.

One of the main objects of the invention is to provide a device of the character stated of simple and very durable construction which may be quickly and easily applied. A further object is to provide a supporting device which is easily portable so as to be carried from one window to another, and may be folded so as to occupy a minimum of space when not in use. Another object is to provide a device having means for supporting a container for the washing solution and also means for supporting cloths used during the washing operation. Further objects will appear from the detailed description.

30 In the drawings:

Figure 1 is a front view of a window shelf constructed in accordance with my invention as applied.

Fig. 2 is a side view of the same.

35 Fig. 3 is a top plan view.

Fig. 4 is a section taken substantially on line 4-4 of Fig. 3.

Fig. 5 is a section on line 5-5 of Fig. 4.

Fig. 6 is a section on line 6-6 of Fig. 1.

40 Fig. 7 is a fragmentary detail showing the device as used in connection with a window casing not provided with a nose piece or sill.

Broadly stated, this supporting device 45 comprises two frames which are pivoted together at their outer ends, one designed to fit snugly within the other when the device is in folded condition, so as to occupy very little space. The main supporting frame A 50 is provided with the end pieces or bars 1 and 2 which are connected at their inner ends by the brace piece 3. The outer ends of these bars are pivotally secured to the bars 4 and 5 of the brace frame B, the outer 55 faces of bars 1 and 2 fitting snugly against the inner faces of bars 4 and 5. The lat-

ter bars are connected by the crossed braces 6 and 7 which serve to rigidly maintain them in proper spaced relation. This brace frame, when raised, fits snugly about the 60 inner supporting frame A. When in operative position, the bars 4 and 5 of the brace frame have their outward movement from the supporting frame positively limited by the folding braces 8 and 9 secured to bars 1 and 1, and 2 and 5, respectively. These braces are formed from two lengths of material or links the overlapping ends of which are pivotally secured together, in the usual manner. End bar 1 70 of supporting frame A is provided, in its outer face, with a recess 10 which is of such depth as to receive within it the brace 8 when folded, the other bar 2 of the supporting frame being provided with a 75 lateral recess for the same purpose. By this means, the brace frame B can be folded upwardly so as to fit snugly about the end bars of the main supporting frame, and the braces connecting these two frames are positioned between the bars of the frames so as to be protected thereby and not project beyond the outline of the device.

The end bars 1 and 2 of the main supporting frame A are connected by a series 85 of transverse slats 11 secured thereto in parallel spaced relation. Two guide strips 12 and 13 are secured to the underfaces of two of these slats. These strips are rabbeted to receive guide tongues formed at the ends 90 of connecting bars 14 which correspond in thickness to the guide strips 12 and 13. A plurality of strips 16 corresponding in width to the spaces between the slats 11 are secured to the strips 14 and 15 so as to be 95 slidably supported thereby. The outer ends of strips 16 are secured in an end bar 17 by dove-tail joints. This end bar 17 is adapted to fit snugly in a recess formed by cutting out the inner edge portions of the ends of the slats 11 to which the guide strips 12 and 13 are secured, and cutting off the ends of the intermediate slats flush with the outer face of end bar 2 of the supporting frame. The strips 14, 15, and 16, together with the 105 end bar 17, constitute a supplemental support which is slidably mounted in the main supporting frame A and may be drawn out so as to extend laterally of the same, the outward movement of this supplemental support being positively limited by engagement of strip 15 with bar 2, and its inward

movement being limited by engagement of bar 17 with this bar. When in its outermost position, this supplemental support provides means for supporting a bucket of water or a 5 washing solution to be used in washing the window panes.

As will be noted more particularly from Fig. 3 of the drawings, the upper end portion of the bracing bar 4 is turned upward 10 and inward at an obtuse angle to provide a supporting arm 18 at the upper end thereof which projects above bar 1 of frame A when brace bar 4 is in operative position, the arm 18 being disposed approximately vertical. 15 The brace arm 5 is provided, at its upper end, with a similar supporting arm 19. These two arms are connected by the spaced slats 20 and the brace bar 21 secured thereto. The arms 18 and 19 and the slats and 20 brace bar constitute a back or guard for the outer end of the support A and serve to prevent a person from accidentally stepping backward off of the support. Suitable 25 guide strips 22 and 23 are secured on the outer face of the slats 20. These guide strips receive blocks 24 projecting outwardly from rods 25 slideable between the slats. These rods are provided, at their outer ends, with upwardly directed fingers 26. When the rods 25 are in their outermost 30 position they provide racks upon which may be hung the cloths used in washing and wiping the window panes. When the rods are in their innermost position, the fingers 26 35 are in engagement with the ends of the upper slat 20 and thus act to positively limit the inward movement of the rods, the outward movement of which is limited by the blocks 24 as will be understood.

40 A downwardly directed securing hook 27 is secured to the inner end of each of the end bars of the main supporting frame A. These hooks are adapted to engage about the inner edge portion of the window sill or bar 28. 45 When the hooks are thus engaged about the window bar, the inclined bracing bars 4 and 5 engage the outer surface of the wall 29 of the building, the main supporting frame A being thus rigidly maintained in horizontal 50 position. To accommodate walls of different thicknesses the end bars of the main frame A and the brace frame B are provided with a series of spaced apertures for receiving the bolts which secure the end of 55 the foldable braces, as more clearly shown in Fig. 2 of the drawings. By this arrangement, the angle of the bars 4 and 5 of the

brace frame to the bars 1 and 2 of the main frame, when in operative position, may be varied slightly, as will be evident. In the 60 event that the window casing is not provided with the usual sill or bar 28, a rod 30 of any suitable material may be placed across the window casing so as to be engaged by the hooks 27, this bar serving in this manner to 65 secure the inner end of the main supporting platform A.

While I have described this device as used more particularly for washing windows, it 70 will be evident that it may be used for many other purposes, such as a shelf for supporting food stuffs which it is desired to keep cool, a support for flower boxes, or similar articles, etc. When not used for cleaning windows, it 75 may be readily folded so as to occupy but little space and can be easily transported from one window to another. When thus folded, the device is free from all projections, and the braces for securing the supporting frame to the bracing frame are completely inclosed 80 so as to be protected from injury. There 85 may be slight changes made in the construction and arrangement of the different parts of my invention without departing from the field and scope of the same and I intend to include all such variations, as fall within the scope of the appended claim, in this application in which a preferred form only of my invention is disclosed.

What I claim is:

In a device of the character described, a main supporting frame, a bracing frame having its end bars pivotally secured intermediate their ends to the outer ends of the end bars of the main frame, the end bars of the bracing frame having their upper end portions angularly disposed so as to provide vertical supporting arms when the bracing frame is in operative position, foldable braces connecting the two said frames, slats 95 secured to the said vertical supporting arms of the end bars of the bracing frame so as to form therewith a guard at the outer end of said main supporting frame, and members 100 slidably mounted between said slats 105 adapted, when in extended position, to support cloths hung thereon so as to be readily accessible to a person using the device.

In testimony whereof I affix my signature in presence of two witnesses.

JOHN E. BURNS.
